US0D1037734S

(12) United States Design Patent (10) Patent No.: US D1,037,734 S
(45) Date of Patent:  Aug. 6, 2024

(54) TABLE

(71) Applicant: E15 Design und Distributions GmbH,
Frankfurt am Main (DE)

(72) Inventor: David Chipperfield, London (GB)

(73) Assignee: E15 Design und Distributions GmbH,
Frankfurt am Main (DE)

() Term: 15 Years

(21) Appl. No.: 35/517,928

(22) Filed: Jul. 11, 2023

(80) Hague Agreement Data

Int. Filing Date: Jul. 11, 2023

Int. Reg. No.: DM/230406

Int. Reg. Date: Jul. 11, 2023

Int. Reg. Pub. Date: Jul. 28, 2023

(51) LOC (14) Cl. 06-03

(52) U.S. Cl.

USPC D6/691.8
